Atty.

UNITED STATES PATENT OFFICE.

ARTHUR O. HUBBARD, OF ROBBINSDALE, ASSIGNOR TO WILLIAM R. SWEATT,
OF MINNEAPOLIS, MINNESOTA.

WHEELBARROW.

SPECIFICATION forming part of Letters Patent No. 487,053, dated November 29, 1892.

Application filed April 29, 1892. Serial No. 481,111. (No model.)

To all whom it may concern:

Be it known that I, ARTHUR O. HUBBARD, a citizen of the United States, residing at Robbinsdale, in the county of Hennepin and State 5 of Minnesota, have invented certain new and useful Improvements in Wheelbarrows, of which the following is a specification.

This invention relates to wheelbarrows; and it consists in the manner of constructing the 10 "tray" or body portion of the vehicle, as hereinafter shown and described, and specifically pointed out in the claims.

In the drawings, Figure 1 is a sectional side elevation, and Fig. 2 is a plan view, of a 15 wheelbarrow embodying my invention. Fig. 3 is a cross-sectional view on the line X X of Fig. 1. Fig. 4 is an enlarged sectional view of the tray, illustrating the manner of securing the sections together. Fig. 5 is an enlarged sectional detail of a portion of the barrow-frame, illustrating the manner of connecting the parts together.

This invention consists in forming the tray or body portion of a wheelbarrow of a series 20 of narrow curved stave-like strips A, so formed that when their edges are brought together and the united sections bent in curved lines and secured firmly together the whole will 25 assume a dish-like shape of the proper form.

In the drawings in Figs. 1, 2, and 4 the sections A are shown connected by tie-rods b', passing through them and secured by rivets or nuts b² in the outer sections. The sections 30 may also be secured by metal bands across the ends of the sections or in any other suitable manner, as I do not wish to be confined to any specific method of securing the sections together. This method of construction forms a very simple, compact, and durable tray, 35 which may be readily constructed from small narrow strips, thus combining strength with cheapness. It also insures a very strong construction of a tray, which will resist the heavy strains or rough usage to which such vehicles 40 are subjected. The sections can be so formed as to give almost any required shape to the tray; but the form shown is the preferable one.

The frame for supporting the tray and to which the wheel D is journaled consists of

the main side bars B' with the legs B² crossing them at a backwardly and downwardly trending angle and bolted thereto at their crossing points, as shown at a'. The upper ends of the legs project above the side bars and are bolted beneath the forward portion 55 of the tray, as at a², while the lower ends are connected by a cross-bar B³. Two braces B⁴ are bolted at a³ to the side bars and with their upper ends projecting above the side bars and supporting the rear portion of the tray, 60 as shown, while their lower ends rest upon the upper inclined surface of the legs B², opposite to the cross-bar B³, so that one bolt a⁴ 65 may be utilized to connect the three parts B⁴, B², and B³ together at their meeting points. This is an important feature of my invention, 70 as it not only greatly simplifies the construction, but renders the frame more substantial and less liable to disarrangement. It also reduces the number of bolt-holes required through the parts, and thereby lessens the chances for breakage.

Having thus described my invention, what I claim as new is—

1. As a new article of manufacture, a wheelbarrow-tray formed of narrow strips with curved contiguous edges, whereby the proper dishing form is secured when said sections are bent and united, substantially as and for the purpose set forth. 75

2. In a wheelbarrow, the side bars B', supporting the tray and between which the wheel D is journaled, the legs B², inclining backward and downward and secured to said side bars, cross-bar B³ beneath the lower portion 80 of said legs, and front braces B⁴, secured to said side bars and with their lower ends resting upon said inclined legs opposite said cross-bars, whereby one bolt a⁴ may be utilized to secure the legs, bars, and braces together, 85 substantially as and for the purpose set forth. 90

In testimony whereof I have hereunto set my hand in the presence of two subscribing witnesses.

ARTHUR O. HUBBARD.
